CRIB ROCKING MECHANISM

Bruno Condemi, Yardville, N. J.

Application November 1, 1950, Serial No. 193,454

3 Claims. (Cl. 5—109)

1

This invention relates to mechanisms and devices for imparting a reciprocative or a rocking movement to baby cribs, and the like.

One of the principal objects of the present invention is to provide an electrical unit, of simple and economical construction, for effecting a delayed reciprocative movement of a crib, or the like, so that there is a period of rest at the end of each movement before the crib is started on its return movement of each cycle.

Another, and important, object of the present invention is to provide a mechanism for effecting reciprocative movement of a crib, or the like, which may easily be connected to cribs of different widths or lengths, depending on whether the movement is intended to be lengthwise of the crib, or transversely.

A further object of the present invention is to provide a mechanism for the purpose mentioned in which the mechanism is housed to prevent injury to children, or others.

A still further object of this invention is to provide a mechanism for the purpose mentioned in which the tracks, motor, sprocket wheels, chain and control switch are of conventional types which can be purchased on the open market at relatively low prices.

Other objects and advantages of the invention will appear from the following specification and reference to the accompanying drawings showing one embodiment of the present invention, in which:

Fig. 1 is a sectional view, in side elevation, through a crib and the mechanism of the present invention, taken partially on the line 1—1 of Fig. 2.

Fig. 2 is a section, in end elevation, taken partially on the line 2—2 of Fig. 1.

Fig. 3 is a perspective view of the front end of the mechanism, with the housing removed therefrom.

Fig. 4 is a perspective view of the mechanism with the housing in position over the mechanism.

Referring to the drawings in which like numerals designate like parts in the several views, the crib 10 is provided with grooved rollers 12 which are adapted to roll on a pair of tracks 14, which have narrow treads 16 upon which the rollers 12 travel. Pairs of transverse, and overlapping bars 18, having registering longitudinal slots 20 are secured to the inner edges of the tracks, by suitable means, such as rivets 22, so that they will be rigid with the tracks.

The electrically operated mechanism, or unit 24 includes a motor 26, having a drive sprocket

2 wheel 28, mounted on one end of a base 30, and a driven sprocket wheel 32 mounted in a bearing 34 on the opposite end of the base 30 with a sprocket chain 36 operatively connecting the two sprocket wheels 28 and 32. A connecting bar 38, having therein a slot 40, is pivoted at one end to a link pivot pin 42 of the chain 34. This pin 42 projects outwardly from the chain, and the bar 38 has a boss 44 on its inner side to space the bar away from contact with the chain. The slotted portion of the bar 38 is slidably connected to a transverse pin 46 which projects from one side of a cross rail 48, carried by the crib 10, into the slot 40. If desired, a block of rubber 46, or other suitable resilient element, may be inserted in the outer end of slot 40 to cushion the contact of the end of the slot with pivot pin 46.

The base 30 is secured to the bars 18 by means of bolts 50 which project through registering belt holes in the base and through the slots 20 of the pairs of bars. When the nuts 52 are loosened the tracks 14 may be adjusted toward or from each other, and, when tightened, these nuts clamp the base 30 and the tracks rigidly together in adjusted position. In this manner the tracks 14 may be spaced, as desired, for cribs of different widths, so that the bar 38 will be in proper position for connecting to the pin 46 on rail 48.

30 A housing 54, having a longitudinal slot 56 along one edge of its top portion, is secured to the base 30 by means of screws, or bolts 58, which project through ears 60 carried by the lower edges of the housing. The height of the housing is somewhat less than that of the wheels 28 and 32, to permit the chain 36 and connecting bar 38 to project through and move freely in the slot 56. The housing may be made of enameled metal, or other suitable material, and it not only protects children, and others, from injury by the motor and other moving parts, but imparts a finished and attractive appearance to the unit. A shallow pan 62 may be placed under the chain 36 to catch any oil that may drip therefrom.

An extension electric cord 64 can be used to connect the motor to a wall socket 66, and a switch 68 connected in the electrical circuit to start and stop the motor 26 may be placed on the crib or, if desired, in a remote location, such, for example, as in a different room or on a different floor from the one occupied by the crib 10.

In Fig. 1 the bar 38 is shown in full lines just as it has completed movement of the crib 10 to the right, with the chain 36 traveling in the direction of the curved arrow. At this point the

crib will remain at rest on the tracks 14 until the pin 42 travels around the outer rim of the wheel 32, the bar 38, in the meantime, sliding outwardly on the pin 46, this being permitted by slot 40. After pin 42 passes the vertical center line of the pin 46, the bar 38 will be drawn inwardly by the travel of the chain until the upper end of slot 40 reaches pin 46, at which time the crib 10 will be drawn to the left until it reaches the position shown in dotted lines. 10 The bar 38 will then be in the position also shown in dotted lines. With the chain 36 traveling in the same direction indicated, the connecting bar 38, as shown in dotted lines, will adjust itself on the pin 46 and draw the crib 10 back to the position shown in full lines. This delayed reciprocative movement will continue as long as the motor runs, and it may be instantly stopped by actuating switch 68.

The entire unit may be easily applied to any 20 crib by providing the rail 48 with pin 46 for connection in the slot 40 of connecting bar 38. Also, the distance of travel of crib 10 on tracks 14 may be increased or reduced by lengthening or shortening the base 30 of the rocking unit.

Changes in the details of construction may be made in my improved mechanism without departing from the spirit and scope of my invention. For example, it is obvious that pulleys and a belt, although not so efficient, could be 30 substituted for the sprocket wheels and chain. Also other detail devices for permitting lost motion between the connecting bar and the crib could be substituted for the slot 40. Therefore, it should be understood that the specific embodiment of my invention shown in the drawings, and described in the specification, is intended to be illustrative, only, and not restrictive thereto.

I claim:

1. An electrical mechanism for effecting reciprocal movement of a crib having supporting rollers, said mechanism comprising a pair of tracks for said rollers, a base attached to said tracks, an electric motor mounted on one end of said base and having a drive sprocket wheel, 40 a driven sprocket wheel mounted on the other

end of said base, a sprocket chain connecting said drive sprocket wheel and driven sprocket wheel, a connecting bar pivoted at one end to said sprocket chain and at its other end to said crib, means carried by said bar and cooperative with said crib to permit lost motion between said bar and said crib during portions of travel of said sprocket chain; and a switch for starting and stopping said motor.

2. An electrical mechanism for effecting reciprocal movement of a crib having supporting rollers, said mechanism comprising a pair of tracks for said rollers connected by pairs of opposed, transverse bars having their inner end portions in adjustable overlapping relation, registering parallel slots in said bars, a base mounted on the upper of said bars and having bolt holes registering with said slots, bolts projecting through said bolt holes and slots and having nuts on one end thereof for clamping said base and bars together, a motor mounted on one end of said base and having a drive sprocket wheel, a driven sprocket wheel mounted on the other end of said base, a sprocket chain connecting said sprocket wheels, a bar pivoted at one end to said chain and having a longitudinal slot in its other end for engagement with a pivot pin on a crib, and a control switch for starting and stopping said motor.

3. An electrical mechanism according to claim 2, including a housing inclosing said motor, chain and sprocket wheels, and having a slot in its top portion through which the upper portions of said chain, bar and sprocket wheels project and move.

BRUNO CONDEMI.
